DESIGN FOR A GLOW LAMP

Aaron H. Hoffeditz, Sacramento, Calif.

Application August 26, 1948, Serial No. 148,301

Term of patent 3½ years

(Cl. D48—20)

To all whom it may concern:

Be it known that I, Aaron H. Hoffeditz, a citizen of the United States, residing at Sacramento, in the county of Sacramento and State of California, have invented a new, original, and ornamental Design for Glow Lamp, of which the following is a specification, reference being had to the accompanying drawing, forming a part thereof.

Figure 1 is a front perspective view of a glow lamp, showing my new design.

Figure 2 is a rear elevational view of the same.

Figure 3 is an end elevational view of the device.

I claim:

The ornamental design for a glow lamp, as shown.

AARON H. HOFFEDITZ.
